UNITED STATES PATENT OFFICE.

CLARENCE M. EASON, OF MOLINE, ILLINOIS, ASSIGNOR TO HYATT BEARINGS
DIVISION, GENERAL MOTORS CORPORATION, OF NEWARK, NEW JERSEY, A
CORPORATION OF DELAWARE.

DYNAMOMETER.

1,424,888.

Specification of Letters Patent. Patented Aug. 8, 1922.

Application filed May 20, 1920. Serial No. 382,727.

To all whom it may concern:

Be it known that I, CLARENCE M. EASON, a citizen of the United States, residing at Moline, in the county of Rock Island and 5 State of Illinois, have invented certain new and useful Improvements in Dynamometers, of which the following is a specification.

The present invention relates to a dynamometer for use in recording a draw bar 10 pull in a tractor or the like; and the object of the invention is to provide a simple and at the same time rugged piece of mechanism which will be well adapted to withstand the heavy strains imposed upon it during a test.

15 The invention consists essentially in the provision of a pair of co-operating compression heads which bear upon a rubber capsule 20 containing oil or other fluid, which is thus subjected to variable pressure, depending 20 upon the measure of the draw bar pull.

Further objects will appear from a detailed description of the invention, which consists in the features of construction and combinations of parts hereinafter described 25 and claimed.

In the drawings:

Figure 1 is a side elevation of the dynamometer;

Fig. 2 is a sectional elevation of the same; 30 and

Fig. 3 is an end view of the same.

The dynamometer comprises a pair of connecting eyes or loops 10 and 11, one of which is intended to connect with the draw bar of 35 a tractor, and the other with the draft connection of a plow or the like. The eye connection 10 is centrally secured to a proximate cross head 12 and a distant cross head 13, through the ends of which cross heads are 40 entered a pair of spacing bolts 14 which give to the structure a rectangular formation.

The eye connection 11 is likewise secured to a proximate cross head 15 and a distant cross head 16 through the medium of spacing 45 bolts 17.

The two members thus described constitute in effect interlocked relatively movable frames, each adapted to impart a thrust in the direction of pull of the respective eye 50 connections. In order to prevent displacement of the members in other than a longitudinal direction, each of the eye connections is formed to provide a shank 18 which enters a socket 19 in the adjacent cross head of the

opposing companion member. The cross 55 head 13 bears against the end face of a compression head 20, which is provided with a longitudinal center bore 21 closed at the outer end by a countersunk packing disk 22 to prevent the escape of fluid, and the compression head is provided in its acting face with a circular recess 23 within which is located a rubber capsule 24 adapted to contain oil or other fluid. The opposite side of the capsule is subject to the pressure of a compression disk 25 which coacts with and complements the action of the compression head 20, being of a size to enter the mouth of the recess 23 within which the rubber capsule is located. 70

The capsule is provided at the center of its inner face with a metallic nipple 26, which is flared at its inner side to bear against the marginal rubber surface of the capsule, which serves to clamp the rubber between 75 the flared end of the nipple and the adjacent metal of the orifice 27, which latter is shouldered at the point 28 to provide a bearing for contact of a pair of nuts 29 on the tip end of the nipple, so that as the nuts are 80 screwed down they will draw the flared inner end of the nipple into clamping engagement with the rubber of the capsule, thereby effecting a pressure tight joint of a nature to relieve the rubber from the disruptive effects of compressive action. 85

The nipple is provided through its center with a port 30 which communicates with the center orifice 21, and the latter has extending laterally therefrom a discharge port 31 90 which connects with a flexible hose or tube 32 through the medium of a coupling 33. The port 31 may be closed by the manipulation of a needle valve 34 extending into axial alignment with the port 31 through the opposite side of the compression head. 95

In use the flexible tube 32 is connected with a suitable recording instrument responsive to variations in pressure, and the draw bar connections 10 and 11 are connected with 100 the tractor or other implement under test and the co-operating plow or other trailer. The interlinking of the two elements composing the dynamometer serves to impart a thrust in each direction against the interposed capsule, which thus is subject to the entire draft pull and will respond to variations in pressure, but without disruptive ef- 105

fect, owing to the fact that the rubber capsule is adequately supported on all sides by the surrounding metallic walls. The pressure imposed upon the liquid will be transmitted through the tube 32 to the recording instrument, which serves to indicate a record of the same. The invention is extremely simple and rugged in construction and compact in structure, and at the same time is so built that most of the parts are interchangeable, which is an advantage from a manufacturing standpoint.

I claim:

1. In a dynamometer the combination of attaching members, a proximate and a distant cross head, the spaced side connections for each of the attaching members standing in angular relation to one another and subtending an interior space, the cross heads and attaching members comprising open compression frames in interlinked relation, oppositely disposed compression members carried by the respective compression frames an interposed capsule for containing liquid located between the compression members and within the space subtended by the compression frames, and a flexible connection in communication with the interior of the capsule for transmitting variations of pressure, substantially as described.
2. In a dynamometer the combination of two attaching members, a proximate and a distant cross head, a connection for each attaching member forming in effect interlinked compression frames subtending an interior space, interengaging means for guiding the adjacent cross heads of the respective pairs in their movements toward and from one another, a compression member carried by the distant cross head of each frame, said compression members acting toward the center in opposition to one another, one of the compression members being recessed and the other being of a size to enter said recess, a flexible capsule located in said recess and subject to compression from opposite sides and a tube in communication with the interior of the capsule for transmitting variations of fluid pressure, substantially as described.
3. In a dynamometer the combination of two attaching members, a proximate and a distant cross head, a connection for each attaching member forming in effect interlinked compression frames subtending an interior space, interengaging means for guiding the adjacent cross heads of the respective pairs in their movements toward and from one another, a compression member carried by the distant cross head of each frame, said compression members acting toward the center in opposition to one

another, one of the compression members being recessed and the other being of a size to enter said recess, means for confining a fluid within said recess, and a flexible tube in communication with the space containing the fluid, substantially as described.

4. In a dynamometer the combination with attaching members, a proximate and a distant cross member and spaced side connections for each of the attaching members comprising open compression frames in interlinked relation and standing in angular relation to each other, oppositely disposed compression members acting toward the center, said members in conjunction affording a sealed recess for containing a fluid and a tube in communication with said recess for transmitting variations of fluid pressure, substantially as described.

5. In a dynamometer, the combination of attaching members, a proximate and a distant cross head and connections for each of the attaching members, forming in effect interlinked compression frames, compression members carried by the respective distant cross heads and acting in opposition to one another, one of the compression members being recessed in its acting face and bored through its center, a flexible capsule located within the recess and provided with a perforated clamping nipple in communication with the center bore, and the other compression member being of a size to enter the recess in the first compression member and bear against the capsule therein located, the recessed member having a port leading from the center bore for transmitting variations in pressure to a recording instrument, substantially as described.

6. In a dynamometer, the combination of attaching members, a proximate and a distant cross head and connections for each of the attaching members, forming in effect interlinked compression frames, compression members carried by the respective distant cross heads and acting in opposition to one another, one of the compression members being recessed in its acting face and bored through its center, a flexible capsule located within the recess and provided with a perforated clamping nipple in communication with the center bore, and the other compression member being of a size to enter the recess in the first compression member and bear against the capsule therein located, the recessed member having a port leading from the center bore for transmitting variations in pressure to a recording instrument, and a needle valve for closing said last named port, substantially as described.

CLARENCE M. EASON
